UNITED STATES PATENT OFFICE.

ROY T. AXE, OF SYRACUSE, NEW YORK, ASSIGNOR TO OLIVER M. EDWARDS, OF SYRACUSE, NEW YORK.

TRAP-DOOR FOR RAILWAY-CARS AND SIMILAR STRUCTURES.

1,090,092.

Specification of Letters Patent. Patented Mar. 10, 1914.

Application filed October 6, 1910, Serial No. 585,641. Renewed September 20, 1912. Serial No. 721,520.

To all whom it may concern:

Be it known that I, Roy T. Axe, a citizen of the United States, residing at Syracuse, county of Onondaga, State of New York, 5 have invented certain new and useful Improvements in Trap-Doors for Railway-Cars and Similar Structures, of which the following is a full, clear, and exact description, reference being had to the drawings 9 accompanying the same.

This invention relates generally to "trap doors" for railway cars and similar structures, as for instance, such as are used to cover and uncover the steps leading to and 5 from such cars, but more particularly to "trap doors" that have a sliding movement endwise of the axial line of hinging the doors to the platforms, such for instance, as are used to bridge over or cover a space 20 between the car and station platforms to afford a safe and convenient passage from the car to such stations.

One of the objects of this invention is to provide a comparatively cheap and easily 25 operated connection between the main portion of a trap door and the hinging means, whereby such door may be controlled in its sidewise movement by such connection independently of the platform in which the door 30 is hung.

Another object is to provide a comparatively cheap durable and easily operated connection between the door and its hinging means by which the door is given a sidewise 35 movement or a movement substantially lengthwise of the axial line of its hinging to the platform.

Another object is to provide means for connecting the operating devices with the 40 door and hinging means in a manner to guide or control the movement of the door in a sidewise direction.

Other objects will appear from the descriptions hereinafter given.

With these objects in view the invention 45 consists in the construction, combination and arrangement of parts to be hereinafter fully described and particularly pointed out in the claims hereunto annexed and forming a 50 part of this specification.

In operating trap doors having a combined turning and sidewise movement on the hinging means, it has been found desirable to control or guide the main portion of 55 the door in such sidewise movement by

means attached to the door at different points relatively to it and its hinging means. When the main portion of the door is thus connected with the hinging means the points of connection between the door and the axial line of the hinging means should be substantial distances apart so that all portions of the door necessarily travel in the same general line irrespective of the opening in the platform and the axial line of hinging 60 in which it is hung. Portions of such means must also move with the door and also relatively to the axial line of the hinging means as the main portion of the door turns in opening or closing. 65

Figure 1 shows in plan view a trap door and a portion of a car platform illustrating generally the door in position for use when the same has been projected sidewise to bridge over or cover a given space between 70 a car and platform, with the means by which the door is projected and the connection between the door and hinging means, which are there seen in dotted lines. Fig. 2 shows in cross section on line 2-2 of Fig. 1 75 that which is there shown. Fig. 3 shows the trap door in the open and retracted position with a portion of the door and connecting means broken away. These connecting 80 means, hinging means and projecting and retracting means are seen in full lines in this Fig. 3. Fig. 4 shows in cross section and on an enlarged scale a detail of the connection between the guiding or controlling 85 means and hinging means seen in preceding figures. Fig. 5 shows a modified construction of projecting means which, as there seen, is connected directly with the guiding or controlling means instead of being independent thereof as seen in Figs. 1 to 3 of 90 the drawings, a portion of the door and guiding or controlling means being broken away as seen. Fig. 6 shows a portion of the trap door in the closed and projected position with the projecting and guiding or controlling means shown in dotted lines. Fig. 100 7 shows in cross section on line 7-7 that which is seen in Fig. 5. Fig. 8 shows in cross section and on an enlarged scale a manner of connecting the rear part of the 105 trap door with the hinging means.

Like letters of reference, wherever they occur, indicate corresponding parts of the several figures of the drawings.

One embodiment of my invention is illus- 110

trated in Figs. 1 to 4 of the drawings where a specific form of projecting means or means adapted to move the door lengthwise of its axial line is shown, but this specific form of projecting means is not the only form adapted to be used in carrying out the present invention. In this specific form of projecting means the door is projected or retracted in a sidewise direction or lengthwise of the axial line of its hinging to the platform as such door turns on its hinging means and the sidewise movement of the door is proportioned to the movement of the door on its hinging means in opening or closing. 10 This form of projecting means, as D, consists of a bar preferably provided with balls one at each end thereof, one of which engages with a socket d^1 attached or secured to the platform and the one at the other end 15 is connected with a socket d^2 mounted upon the door B adjacent the hinged side thereof and as the door makes its quarter turn in opening or closing, the balls in these sockets have free movement therein so that the door receives a turn on its hinging means, as C, which as seen, is simply a rod c mounted in suitable bearings suitably formed in brackets or other suitable means attached to the platform A in which the door B is to be 20 used. The rear portion of the door is connected with the rod c by the inclosing clips c' clearly seen in dotted lines in Fig. 1 of the drawings. In this specific form of projecting means the extent of projection of the door or retraction is according to the extent of the arc of the circle described by the ball on the bar d which is in engagement with a socket mounted on the door with the socket d' secured to the platform as a center. 25 Other forms of projecting or retracting means than that shown in Figs. 1, 2 and 3 may be employed if desired and differently arranged and connected in order to project or retract the door, such for instance, as is 30 shown in Figs. 5, 6 and 7.

The guiding or controlling means for guiding and controlling the movement of the door sidewise includes, as shown in Figs. 1, 2 and 3, two substantially parallel bars E, E' arranged beneath the door and pivotally connected at one end to the door B near the free side thereof and at the other end to parts projecting radially from the rotatable collars e , e' , these collars being rotatable 50 with the barrel or rod c which is movable about a fixed axis and is mounted in suitable bearings c^2 c^3 attached to the platform. The axes connecting the ends of the bars E, E' to the door and the collars e , e' extend crosswise of the longitudinal axis of the rod c . These bars, as E, E', have a swinging movement relatively to the door B the rod c and the platform A as the door is projected or retracted and they also have a turning movement on the hinging means as the door is 55

opened or closed and by reason of the pivotal connections of these bars with the door and hinging means the door is controlled or guided at two different points as it is projected or retracted and it moves easily and requires but a small force to be applied in operating the door. With the form of projecting and retracting means shown in these Figs. 1, 2 and 3, the door is projected or retracted while being opened or closed, and moves slightly toward and from the longitudinal axis of the barrel c but the specific projecting and retracting means is no material portion of the present invention because such controlling or guiding means is adapted for use with any form of projecting means that the constructor sees fit to use. 70 75 80

Another embodiment of the present invention is illustrated in Figs. 5, 6 and 7 of the drawings and as there shown the projecting and retracting means are connected directly with the controlling or guiding means and act upon the door through such controlling means in projecting or retracting the door. As here shown, there are two levers or bars, 85 as E^2 E^3 , each of which is pivotally connected at one end to the door B and fulcrumed at x x' upon arms, as d^4 d^5 , respectively, secured to the rod or tube c of the hinging means C, which bars or levers at 90 their free ends are provided with anti-friction rollers in position to coat with cam surfaces, as e^2 e^3 , respectively. The rod or tube c is mounted in brackets c^2 , substantially as shown in Figs. 1, 2 and 3. 95 100

The arms d^4 d^5 , which are secured to the rod or tube c simply turn with such rod or tube as it turns in the brackets c^2 attached to the platform in the opening and closing of the door, such arms forming fulcrums for 105 the levers or bars E^2 E^3 , respectively. The anti-friction roller in the free end of the bar or lever E^2 coacts with the cam surface e^2 in retracting the door as shown in Fig. 5 and the anti-friction roller in the free end 110 of the lever or bar E^3 coacts with the cam surface e^3 in projecting the door from the position seen in Fig. 5 to that seen in Fig. 6, as the door turns on its hinging means. The pivotal points at which one end of each 115 of the bars or levers is pivotally connected to the door are at equal distances from the axial line of the hinging means and this is also the case with the fulcrum points, as x x' , of said levers and as a result the movement of the door lengthwise of its axial line of hinging is fully controlled and guided in the projection and retraction of the same independently of the opening in which the door is mounted. 120 125

In the construction shown in Figs. 5, 6 and 7 the door is moved in the arcs of circles of which the fulcrum points x x' are the centers as it is moved sidewise or lengthwise of the axial line of its hinging during the turn- 130

skilled in this art that any means may be used to project and retract the doors whether such means act upon the door in the manner herein set forth or in any other manner, and also whether it be while the door is turning or when it is in any given position, because the means by which this work is accomplished is no material portion of the present invention.

The rear portion of the door in each of the embodiments herein shown is connected with the hinging means by clips, as c^1 , as seen more particularly in Figs. 1, 3, 5, 6 and 8 of the drawings and this portion of the door in each case is connected with the rod or tube c of the hinging means, but it may be otherwise so long as the door as a whole may turn on its hinging means and move generally in a sidewise direction to close the opening in the platform.

What is herein shown and described will naturally suggest to those skilled in the art other specific forms of guiding or controlling means and modifications in that which is herein shown and described which, while varying in form or details of construction or arrangement will have substantially the same method or mode of operation in accomplishing essentially the same work as is the case with that which is herein set forth, hence I do not desire to limit my invention to the specific forms, constructions or arrangements of parts or devices herein shown and described, but desire to include all forms, constructions and arrangements that are within the spirit of my invention.

40 What I claim as new is:—

1. The combination with a car platform provided with a step opening and a trap door movable about an axis to close and expose said opening and movable in a direction substantially lengthwise of said axis for projecting a part of its length beyond the plane of the side of the car and for withdrawing such portion, of a hinge element supported from the car and movable about a fixed axis, and means for connecting the door to said element including a part movable about an axis shiftable with said element, substantially as and for the purpose described.

2. The combination with a car platform provided with a step opening and a trap door movable about an axis to close and expose said opening and movable in a direction substantially lengthwise of said axis for projecting a part of its length beyond the plane of the side of the car and for withdrawing such portion, of a hinge element supported from the car and movable about a fixed axis, and means for connecting the door to said element including a part pivotally connected at one end to said element

and at its opposite end to the door, substantially as and for the purpose specified.

3. The combination with a car platform provided with a step opening and a trap door movable about an axis to close and expose said opening and movable in a direction substantially lengthwise of said axis for projecting a part of its length beyond the plane of the side of the car and for withdrawing such portion, of a hinge element supported from the car and movable about a fixed axis, and means for connecting the door to said element including a part having a swinging movement relative to said element, substantially as and for the purpose set forth.

4. The combination with a car platform provided with a step opening and a trap door movable about an axis to close and expose said opening and movable in a direction substantially lengthwise of said axis for projecting a part of its length beyond the plane of the side of the car and for withdrawing such portion, of a hinge element supported from the car and movable about a fixed axis, and means for connecting the door to said element including parallel arms pivotally connected respectively to said element and to the door on the side of the longer axis thereof remote from said element, substantially as and for the purpose described.

5. The combination with a car platform provided with a step opening and a trap door movable about an axis to close and expose said opening and movable in a direction substantially lengthwise of said axis for projecting a part of its length beyond the plane of the side of the car and for withdrawing such portion, of means for operating on the door adjacent one side edge thereof for shifting the door in said lengthwise direction, and means, including a part cooperating with the door adjacent the opposite side edge thereof, for supporting and guiding the door during its movements, substantially as and for the purpose specified.

6. In combination with a car platform, a trap door movable about an axis and having an additional movement in a direction at an angle to the path of movement of the door about its axis, and connections between the platform and the trap door including means movable about said axis, and means extending beneath the door and connected to the door in proximity to its free side and connected to the first-mentioned means, said second-mentioned means turning with the first-mentioned means to turn the door therewith and being movable relatively to the first-mentioned means in the additional movement of the door, substantially as and for the purpose set forth.

7. In combination with a car platform having an opening therein, a trap door as-

4

sociated with the opening and having a pivotal and a sliding movement, and connections between the platform and the door for controlling the sliding movement of the 5 door, said connections including means located adjacent one side edge of the door and movable about the axis of the pivotal movement of the door, and other means extending beneath the door and connected to the 10 first-mentioned means and connected to the door in proximity to the opposite side edge thereof, substantially as and for the purpose described.

8. In combination with a car platform, a 15 trap door movable about an axis and having an additional movement in a direction at an angle to the path of movement of the door about its axis, and connections between the platform and the trap door including means 20 movable about said axis, and a bar arranged beneath the door and connected at one end to the door and at its opposite end to said means, the bar turning with said means to turn the door therewith and being movable 25 relatively to said means in the additional movement of the door, substantially as and for the purpose specified.

9. In combination with a car platform, a trap door movable about an axis and having 30 an additional movement in a direction at an angle to the path of movement of the door about its axis, and connections between the platform and the trap door including means movable about said axis, and a pair 35 of members arranged one in advance of the other and connected to the door and to said means, the members turning with said means to turn the door therewith and being movable relatively to said means in the additional 40 movement of the door, substantially as and for the purpose set forth.

10. In combination with a car platform, a trap door movable about an axis and having 45 an additional movement in a direction at an angle to the path of movement of the door about its axis, and connections between the platform and the trap door including means movable about said axis, and a pair 50 of substantially parallel members arranged one in advance of the other beneath the door and connected to the door and to said means, the members turning with said means to turn the door therewith and being movable relatively to said means in the additional 55 movement of the door, substantially as and for the purpose described.

11. The combination with a car platform having an opening therein, of a trap door 60 associated with the opening and having a pivotal and a sliding movement, and connections between the platform and the door including means movable about the axis for the pivotal movement of the door, and parallel bars connected at corresponding ends

to said means to turn therewith and to move 65 in planes substantially radial to said axis, and connected at their opposite ends to the door, substantially as and for the purpose specified.

12. In combination with a car platform, a trap door movable about an axis and having 70 an additional movement in a direction at an angle to the path of movement of the door about its axis, and connections between the platform and the trap door including means movable about said axis, and means pivotally connected to the door and to the first-mentioned means, said second mentioned means turning with the first-mentioned means to turn the door therewith and moving relatively to the first-mentioned means and the door in the additional movement of the door, substantially as and for the purpose set forth.

13. In combination with a car platform, a trap door movable about an axis and having 80 an additional movement in a direction at an angle to the path of movement of the door about its axis, and connections between the platform and the trap door including 90 means movable about said axis, and a bar arranged beneath the door and connected to the door, the bar being pivotally connected to said means and having its pivotal axis arranged crosswise of the first-mentioned axis, said bar turning with said means to turn the door therewith and moving about its pivotal axis relatively to said means in the additional movement of the door, substantially as and for the purpose 100 described.

14. In combination with a car platform, a trap door movable about an axis and having an additional movement in a direction at an angle to the path of movement of the door about its axis, and connections between the platform and the trap door including means movable about said axis, a bar arranged beneath the door, and pivotal means connecting one end of the bar to the door 110 and connecting the other end of the bar to said means, the axes of the pivotal means extending crosswise of said axis, and the bar turning with said means to turn the door therewith and moving about the axes of 115 said pivotal means relatively to the first-mentioned means and the door in the additional movement of the door, substantially as and for the purpose specified.

15. The combination with a car platform 120 having an opening therein, of a trap door movable about an axis and having an additional movement in a direction at an angle to the path of movement of the door about its axis, and connections between the platform and the trap door including means movable about said axis, parallel members arranged beneath the door, and pivotal

- means connecting corresponding ends of the parallel members to the door and connecting the opposite ends of the members to said means, the axes of the pivotal means extending crosswise of said axis, and said parallel members turning with said first-mentioned means to turn the door therewith and moving about the axes of the pivotal means relatively to the first-mentioned means and the door during the additional movement of the door, substantially as and for the purpose set forth.
16. In combination with a car platform, a trap door movable about an axis and having an additional movement in a direction at an angle to the path of movement of the door about its axis, and connections between the platform and the trap door including means movable about said axis and provided with a substantially radial engaging part, and means connected to the door and to said engaging part, the second-mentioned means turning with the first-mentioned means to turn the door therewith and moving relatively to the first-mentioned means in the additional movement of the door, substantially as and for the purpose described.
17. In combination with a car platform, a trap door movable about an axis and having an additional movement in a direction at an angle to the path of movement of the door about its axis, and connections between the platform and the trap door including means movable about said axis and provided with a pair of substantially radial engaging parts one in advance of the other, a pair of substantially parallel members beneath the door, and pivotal means connecting said members to the door and to the engaging parts, the pivotal means being arranged with their axes extending crosswise of the first-mentioned axis, and said members turning with the first-mentioned means to turn the door therewith and moving about the axes of the pivotal means relatively to the first-mentioned means and the door in the additional movement of the door, substantially as and for the purpose set forth.
18. In combination with a car platform, a trap door movable about an axis and having an additional movement in a direction at an angle to the path of movement of the door about its axis, and connections between the platform and the trap door including a hinged barrel provided at its ends with fixed substantially radial projections beneath the door, a pair of substantially parallel members beneath the door, and pivotal means connecting said members to the door and to said projections, the pivotal means being arranged with their axes extending crosswise of the first-mentioned axis, and said members turning with the barrel to turn the door therewith and moving about the axes of the pivotal means relatively to the barrel and the door in the additional movement of the door, substantially as and for the purpose specified.
19. In a trap door for car platforms, a hinged support, and a trap door carried by the support and shiftable in a direction parallel to the axis of the hinged support and also shiftable toward and from said axis, substantially as and for the purpose described.
20. In combination with a car platform, a trap door movable about an axis and having an additional movement in a direction at an angle to the path of movement of the door about its axis, and connections between the platform and the trap door including means movable about said axis, means for connecting the hinged side of the door to the first-mentioned means and for guiding said side of the door, and additional means connected to the door and to the first-mentioned means, said additional means turning with the first-mentioned means to turn the door therewith, and moving relatively to the first-mentioned means in the additional movement of the door, substantially as and for the purpose specified.
21. In combination with a car platform, a trap door movable about an axis and having an additional movement in a direction at an angle to the path of movement of the door about its axis, and connections between the platform and the trap door including means movable about said axis, means for connecting the hinged side of the door to the first-mentioned means and for guiding said side of the door, said connecting and guiding means being fixed to one of the parts connected thereby, and additional means connected to the door and to the first-mentioned means, said additional means turning with the first-mentioned means to turn the door therewith and movable relative to the first-mentioned means in the additional movement of the door, substantially as and for the purpose set forth.
22. In combination with a car platform, a trap door movable about an axis and having an additional movement in a direction at an angle to the path of movement of the door about its axis, the trap door being also movable toward and from said axis, and connections between the platform and the trap door including means movable about said axis, spaced apart members for connecting the hinged side of the door to the first-mentioned means and for guiding said side of the door, said members being fixed to the door and being movable laterally relatively to said means when the door moves toward and from said axis, and additional means connected to the door and to the first-mentioned means, said additional means

turning with the first-mentioned means to turn the door therewith and moving relatively to the first-mentioned means in the additional movement of the door, substantially as and for the purpose described.

23. In combination with a car platform, a trap door movable about an axis and having an additional movement in a direction at an angle to the path of movement of the door about its axis, and connections between the platform and the trap door including means movable about said axis, means for connecting a portion of the door to the first-mentioned means and for guiding said portion of the door, and additional means connected to the opposite portion of the door and to the first-mentioned means, said additional means turning with the first-mentioned means to turn the door therewith, and moving relatively to the first-mentioned means in the additional movement of the door, substantially as and for the purpose specified.

24. In combination with a car platform having an opening therein, a rod supported from the platform and associated with the opening, a trap door movable about the axis of the rod and having an additional movement in a direction at an angle to the path of movement of the door about said axis, and means carried by the rod and turning therewith, said means being pivotally connected to the door and movable relatively to the rod in the additional movement of the door, substantially as and for the purpose set forth.

25. The combination with a car platform having an opening therein, a rod supported from the platform and associated with the opening, a trap door movable about the axis of the rod and having an additional movement in a direction at an angle to the path of movement of the door about said axis, parallel members pivotally connected at corresponding ends to the rod and movable about the axis of the rod during the movement of the door about said axis, and pivotal connections between the opposite ends of said members and the trap door, substantially as and for the purpose described.

26. In combination with a car platform having an opening therein, a trap door associated with the opening and movable about an axis and having an additional movement in a direction at an angle to the path of movement of the door about its axis, and connections between the platform and the trap door including means located adjacent one side edge of the door and movable about said axis, said means being provided with a pair of substantially radial engaging parts one in advance of the other beneath the door, a pair of substantially parallel members beneath the door, and pivotal means connecting corresponding ends of the

members to said engaging parts and connecting the opposite ends of the members to the door near the opposite side thereof, the axes of the pivotal means extending crosswise of the first-mentioned axis, substantially as and for the purpose specified.

27. In combination with a car platform having an opening therein, a trap door associated with the opening and movable about an axis and having an additional movement in a direction at an angle to the path of movement of the door about its axis, the trap door being also movable toward and from said axis, and connections between the platform and the trap door including means located adjacent the hinged side of the door and movable about said axis, said means being provided with a pair of substantially radial engaging parts one in advance of the other beneath the door, spaced apart members connecting the hinged side of the door to said means and guiding said side of the door, the members being fixed to the door and being movable laterally relatively to said means when the door moves toward and from said axis, a pair of substantially parallel members beneath the door, and pivotal means connecting corresponding ends of the members to said substantially radial parts and connecting the opposite ends of the parts to the door near the opposite side thereof, the axes of the pivotal means extending crosswise of the first-mentioned axis, substantially as and for the purpose set forth.

28. In combination with a car platform, a trap door movable about an axis and having an additional movement in a direction at an angle to the path of movement of the door about its axis, connections between the platform and the trap door including means movable about said axis, and means connected to the door and to the first-mentioned means, said second-mentioned means turning with the first-mentioned means to turn the door therewith and moving relatively to the first-mentioned means and the door in the additional movement of the door, and a spring for moving the door in one direction about its axis, substantially as and for the purpose specified.

29. In combination with a car platform, a trap door movable about an axis and having an additional movement in a direction at an angle to the path of movement of the door about its axis, connections between the platform and the trap door including a hinged barrel provided at its ends with fixed substantially radial parts one in advance of the other beneath the door, a pair of substantially parallel members beneath the door, pivotal means connecting said members to the door and to said substantially radial parts, the pivotal means being arranged with their axes extending crosswise of the first-mentioned axis, and said

members turning with the barrel to turn the door therewith and moving about the axes of the pivotal means relatively to the barrel and the door in the additional movement of the door, and a spring within the barrel for moving the trap door in one direction about its axis, substantially as and for the purpose set forth.

30. In combination with a car platform having an opening therein, a trap door associated with the opening and movable about an axis and having an additional movement in a direction at an angle to the path of movement of the door about its axis, the trap door being also movable toward and from said axis, connections between the platform and the trap door including means located adjacent the hinged side of the door and movable about said axis, said means being provided with a pair of substantially radial engaging parts one in advance of the other beneath the door, spaced apart members connecting the hinged side of the door to said means and guiding said side of the door, the members being fixed to the door and being movable laterally relatively to said means when the door moves toward and from said axis, a pair of substantially parallel members beneath the door, pivotal means connecting corresponding ends of the members to said substantially radial parts and connecting the opposite ends of the members to the door near the opposite side thereof, the axes of the pivotal means extending crosswise of the first-mentioned axis, and means for effecting the additional movement of the door during the movement of said door about its axis, substantially as and for the purpose set forth.

31. In combination with a car platform, a trap door movable about an axis and having an additional movement in a direction at an angle to the path of movement of the door about its axis, and connections between the platform and the trap door including means movable about said axis, means connected to the door and to the first-mentioned means, said second-mentioned means turning with the first-mentioned means to turn the door therewith and moving relatively to the first-mentioned means and the door in the additional movement of the door, and means for effecting the additional movement of the door during the movement of said door about its axis, substantially as and for the purpose specified.

32. In combination with a car platform having an opening therein, a trap door associated with the opening and movable about an axis and having an additional movement in a direction at an angle to the path of movement of the door about its axis, the trap door being also movable toward and from said axis, and connections between the platform and the trap door including means located adjacent the hinged

side of the door and movable about said axis, said means being provided with a pair of substantially radial engaging parts one in advance of the other beneath the door, spaced apart members connecting the hinged side of the door to said means and guiding said side of the door, the members being fixed to the door and being movable laterally relatively to said means when the door moves toward and from said axis, a pair of substantially parallel members beneath the door, pivotal means connecting corresponding ends of the members to said substantially radial parts and connecting the opposite ends of the members to the door near the opposite side thereof, the axes of the pivotal means extending crosswise of the first-mentioned axis, and means for effecting the additional movement of the door during the movement of said door about its axis, substantially as and for the purpose set forth.

33. A trap door of the character described provided with means connected with a plurality of the portions thereof and adapted thereby to control the sidewise movement of the door when connected with the hinging means or platform of the car, substantially as set forth.

34. A trap door of the character described provided with means a portion of which is engageable with different portions of the door and another portion is engageable with the hinging means or platform and thereby adapted to guide it in a line substantially parallel with the axial line of the hinging means of the door as the door moves lengthwise of such line, when such means is connected with the hinging means or platform, substantially as set forth.

35. A trap door of the character described provided with means connected with different portions thereof and adapted to be connected with the hinging means and thereby guide the door in its movement lengthwise of the axial line of the hinging means, substantially as set forth.

36. A trap door of the character described provided with means pivotally connected thereto at different points and adapted to be pivotally connected to the hinging means and turn with the door on its axial line of hinging and thereby guide the door in its movement lengthwise of such axial line as the door turns in opening or closing, substantially as set forth.

37. A trap door of the character described provided with means connected thereto at different points and adapted to be connected with the hinging means and thereby guide the door in its sidewise movement, and means adapted, when connected in place to project and retract the door in such sidewise direction, substantially as set forth.

38. In a car platform, the combination,

substantially as set forth, of an opening therein, a door for closing such opening, hinging means adapted to permit the door to open and close and also to move lengthwise of the axial line of such means, and means adapted to engage with different portions of the door and with the hinging means and thereby guide the door in its sidewise direction.

10 39. In a car platform the combination, substantially as set forth, of an opening therein, a door for closing such opening, hinging means adapted to permit the door to open and close and also to move lengthwise of the axial line of such means, means adapted to engage with different portions of the door and with hinging means to guide the door in its sidewise direction, and means connecting with the door and platform adapted 15 to move such door in a line substantially parallel with such axial line.

40. In a car platform the combination, substantially as set forth, of an opening therein, a door for closing such opening, hinging means adapted to connect with the door and platform and permit the door to turn thereon and move lengthwise of the axial line thereof, means connectible with the door and platform adapted to project 25 the door in a sidewise direction, and means connected with different portions of the door and with the hinging means to guide the door in its sidewise movement.

41. In a car platform the combination, substantially as set forth, of an opening therein, a door for closing such opening, hinging means adapted to connect with the 30

door and platform and permit the door to turn thereon and move lengthwise of the axial line of such means, means connectible 40 with the door and platform adapted to move the door sidewise, and means connectible with different portions of the door and with the hinging means adapted to guide the door in its sidewise movement.

45 42. In a car platform the combination, substantially as set forth, of an opening therein, a door for closing such opening, hinging means adapted to connect with the door and platform and permit the door to 50 turn thereon and move sidewise, and means consisting essentially of two portions each of which is connected with the door at different portions thereof and to the hinging means so as to move relatively thereto as the door 55 moves sidewise and to move with the door as it turns on the hinging means.

43. In a car platform the combination, substantially as set forth, of an opening therein, a door for closing such opening, 60 hinging means adapted to connect with the door and platform and permit the door to turn thereon and move sidewise, and means pivotally connected to the door at different points thereon and to the hinging means and 65 thereby adapted to move with the door at one point of connection and the door to move relatively to that portion of such means which is pivotally connected with the hinging means.

ROY T. AXE.

Correction in Letters Patent No. 1,090,092.

It is hereby certified that in Letters Patent No. 1,090,092, granted March 10, 1914, upon the application of Roy T. Axe, of Syracuse, New York, for an improvement in "Trap-Doors for Railway-Cars and Similar Structures," an error appears in the printed specification requiring correction as follows: Page 3, transpose lines 1 and 4 as now numbered; and that the said Letters Patent should be read with this correction therein that the same may conform to the record of the case in the Patent Office.

Signed and sealed this 28th day of April, A. D., 1914.

[SEAL.]

J. T. NEWTON,

Acting Commissioner of Patents.
